UNITED STATES PATENT OFFICE.

LOUIS J. GROSKY, OF CLEVELAND, OHIO.

RUBBER FOOTWEAR.

1,105,270.

Specification of Letters Patent. Patented July 28, 1914.

Application filed January 5, 1914. Serial No. 810,252.

To all whom it may concern:

Be it known that I, LOUIS J. GROSKY, a citizen of the United States, residing at Cleveland, in the county of Cuyahoga and State of Ohio, have invented a certain new and useful Improvement in Rubber Footwear, of which the following is a full, clear, and exact description, reference being had to the accompanying drawings.

This invention relates to rubber footwear, including overshoes, rubber boots and similar articles.

The general object of the invention is to greatly increase the length of life of such footwear at a very slight increase in the cost of manufacture. To this end I provide in the heel portion of the footwear, embedded in the rubber thereof, a reinforcing device placed so as to extend beneath and around the rear and sides of the heel of the wearer's shoes, and I make the reinforcing device of such form that it may be effectively vulcanized to the rubber in which it is embedded, so that it can not shift and thereby wear through the adjacent parts.

A further feature of my invention is that it provides a reinforcing device, one size of which may be used for several sizes of overshoes, with a resultant saving in cost of manufacture, and which is so shaped that there will be no sharp corners to cut the rubber and fabric of the overshoe.

My invention is hereinafter more fully explained and the essential characteristics set forth in the claims.

In the drawings, Figure 1 is a perspective view of an overshoe equipped with my reinforcing device; Fig. 2 is a vertical section of the heel portion of such overshoe; Fig. 3 is a perspective view of the reinforcing device, removed; Fig. 4 is an enlarged sectional detail of the heel portion.

As shown in Figs. 1 and 2, A indicates the body of the overshoe, B the under portion of the heel thereof, C and D inner and outer sheets of rubberized fabric constituting the usual wall around the heel and in the bottom, and E an inner heel seat above the heel bottom. My reinforcing device consists of a scoop-shaped member having a bottom plate F and a U-shaped wall G rising from the bottom edge of the bottom plate and inclining rearwardly, and shaped and proportioned to lie between the wall and bottom C and D of the overshoe. This scoop-shaped reinforce is preferably made

of metal stamped from a single sheet, but it may be constructed of other material. The rear portion of the wall G is extended upwardly to such a height that it will reach well upon, if not above the leather heel of the inner shoe of the wearer, and from the rear portion the upper edge of the wall slants forwardly and is curved downwardly to the forward edge of the plate F. The corners between the plate F and the wall G are preferably rounded, as shown. In the bottom plate and side walls of this member are provided perforations H which are filled with a tough rubber compound as shown at I, Figs. 2 and 4, forming a part of layers J and K, of this rubber compound, which are vulcanized to the walls C and D. The rubber compound of the layers J and K is pressed into the perforations H until the rubber of one layer meets the rubber of the other, and is then vulcanized, forming in effect, a rivet through each opening in the reinforce. This positively prevents the shifting of the reinforce, and thereby prevents the edges of the metal from cutting or wearing through either of the walls C and D. The reinforce is further prevented from shifting by knurling its surfaces, as shown at M, forming projections engaging the rubber of the contiguous rubberized fabrics. This knurling may be conveniently accomplished by knurling the flat strip from which the reinforce is formed. To still more firmly secure the reinforcing device to the adjacent rubberized fabric, the rubber of the contiguous rubber layers is vulcanized to the reinforce itself. This is made possible, when the reinforcing device is of metal, by putting the reinforce through a rusting process, making it possible to cause the rubber to adhere very firmly to the metal. When the reinforcing device is thus embedded in the heel portion of the overshoe, and rubber is pressed into the perforations, and the same is vulcanized, it constitutes a unitary part of the overshoe.

Ordinarily the heels of overshoes have to be very well fitted, to the shoe of the wearer in order to get even reasonable service from them. This is not the case with overshoes fitted with my reinforcing device, as it makes little difference, for the wearing qualities will be substantially the same whether the heel of the shoe is one half the area of the heel of the rubber, as is very frequently the case with ladies' shoes, or whether it is sub-

stantially the same, as the stiffness of the reinforce causes the rubber of the overshoe to wear evenly, and the smallness of the inner heel does not cause it to wear through any one spot of the heel of the overshoe. Accordingly, in making the overshoes which are fitted with my reinforce, the size of the heels does not need to vary as greatly as with ordinary overshoes. I find that by 10 shaping the reinforce, as shown and described, that is in the form of a scoop, that it may be fitted into heels varying somewhat in size, and it is only necessary to make a small number of sizes of reinforce to cover 15 the necessary range of sizes of overshoes. For example, one reinforce substantially fitted for the heel of a size three and a half overshoe, may be also used for sizes three and four. This obviates the necessity of 20 making a separate size of reinforce for each particular size and width of heel, greatly reducing the number of sizes of dies required and accordingly, reducing the cost of manufacture.

25 My reinforcing device adds very slightly to the cost of the overshoe. It is entirely invisible when in place. It effectively protects the overshoe at its most vulnerable part, namely: the heel portion adjacent to 30 the junction of the bottom and wall. The wear at the heel portion of the ordinary overshoe comes from two causes. First, the abrading of the rubber by the corners of the heel, the uneven edges of worn heels and 35 nails protruding from heels, second, the leather heel, particularly in the case of ladies' overshoes frequently does not reach the seat, so that there is a continual collapsing and extending of the rubber heel-wall, 40 as the wearer steps. This "bellows" effect, so to speak, quickly cracks and breaks the heel wall. My reinforce protects against both of these dangers. The rough heels and 45 projecting nails cannot reach the outer rubber, and the wall of the reinforce holds the heel portion in shape so that the heel of the leather shoe sinks naturally to the heel seat, and the bellows effect and the consequent wear and breakage is eliminated.

50 Having thus described my invention, what I claim is:

1. The combination with an article of rubber footwear of a scoop-shaped reinforcing device embedded in the bottom and walls 55 of the heel portion and having openings therethrough into which the rubber projects.
2. The combination with a rubber overshoe, of a scoop-shaped reinforcing device embedded in the bottom and wall of the 60 heel portion and having openings there-

through filled with the rubber of the contiguous portions of the overshoe, forming in effect rubber rivets through the reinforcing device.

3. The combination with a rubber overshoe, of a scoop-shaped unyielding reinforcing device having a bottom and an integral wall rising from the sides thereof and embedded in the heel portion of the overshoe and having openings through the bottom 70 and side walls, said openings being filled with the rubber of the contiguous parts.

4. The combination with a rubber overshoe, of a metal reinforcing device consisting of a bottom and an integral wall rising 75 from the sides and rear thereof, and having openings through the bottom and wall and being embedded in the bottom and wall of the heel portion of the overshoe, said openings being filled with the rubber of the contiguous 80 layers of the overshoe, the rubber of said layers coming together within the openings and being vulcanized.

5. The combination with a rubber overshoe, of a scoop-shaped metallic reinforcing 85 device embedded in the bottom and wall of the heel portion of the overshoe and having openings therethrough, said openings being filled with the rubber of contiguous parts, the surface of said reinforcing device being 90 roughened by oxidation to permit vulcanizing the rubber thereto.

6. The combination with a rubber overshoe, of a steel scoop-shaped reinforcing device embedded in the heel portion of the 95 overshoe, the surface of said device being rusted to permit vulcanizing the rubber of the overshoe thereto.

7. The combination with a rubber overshoe, of a scoop-shaped, unyielding reinforcing device having a bottom and integral walls rising from the sides thereof and embedded in the heel portion of the overshoe and having knurled surfaces engaging the 100 rubber of the contiguous parts.

8. The combination with a rubber overshoe, of a steel scoop-shaped reinforcing device embedded in the heel portion of the overshoe, said device having openings therethrough filled with the rubber of the overshoe and having knurled surfaces engaging the rubber of the overshoe, said device being rusted to permit the rubber of the overshoe 110 being vulcanized thereto.

In testimony whereof, I hereunto affix my 115 signature in the presence of two witnesses.

LOUIS J. GROSKY.
